UNITED STATES PATENT OFFICE.

GEORGE R. MEYERCORD, OF CHICAGO, ILLINOIS, ASSIGNOR TO HASKELITE MANUFACTURING CORPORATION, A CORPORATION OF NEW YORK.

WALL SAFE OR VAULT.

Application filed March 26, 1926. Serial No. 97,564.

The present invention relates to structures adapted to be built into houses or other buildings to form substantially airtight closets or vaults, and it has for its object to produce a simple and novel structure in which the exposed wall may be made of comparatively heavy material and the side and rear walls of light metal sheets.

In order to give rigidity to the structure as a whole and prevent distortion, it is necessary to reinforce and stiffen the light metal sheets. The object of the present invention, viewed in one of its aspects, is to reinforce and stiffen the light metal walls of a structure of the kind specified, without the use of any parts other than those required to attach the various wall elements together.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a front view of a structure embodying my invention, mounted so that the front thereof, which contains the door, lies flush with the face of the wall of a building; Fig. 2 is a side view of the structure; Fig. 3 is a section on an enlarged scale taken on line 3—3 of Fig. 1; Fig. 4 is a perspective view showing the top of the structure with the top wall detached; Fig. 5 is a horizontal section through one of the front corners and Fig. 6 is a horizontal section through the vertical joint in the center of the rear wall.

Referring to the drawings, 1 represents the front wall of a square or rectangular shell or casing, having therein a door opening within which is hung a door 2. The wall 1 is made of a metal-sheathed panel of greater width than the structure as a whole, the panel being grooved along vertical parallel lines on the inner side so as to permit the side marginal portions 3 and 4 to be bent back at right angles to the main portion of the panel and form the two front corners of the structure. The two side walls 5 and 6 are made of comparatively thin sheet metal, each consisting of a sheet bent sharply along a vertical line so as to provide a section that will constitute one-half of the rear wall, such sections being indi-

cated at 7 and 8. The side walls are attached to the flanges or wings 3 and 4 of the front wall, by cutting or sawing into the rear vertical edge of each of these wings or flanges a deep narrow slot 9 into which the forward marginal portions of the side walls fit. A plurality of small bolts 10 are passed through the flanges or wings along lines that will intersect the grooves into which the side walls fit; these bolts therefore also passing through the forward marginal portions of the side walls.

The rear wall sections 7 and 8 do not meet, but each extends and fits into a groove 11 in the side of a flat reinforcing rib 12 that extends vertically along the middle of the rear wall. Bolts 13, similar to the bolts 10, pass through this reinforcing rib from front to rear, and through those portions of the rear wall that lie within grooves in the rib.

It will thus be seen that the four side walls of the structure are made of three sheets or panels and a single reinforcing rib, these four elements being rigidly secured together by small bolts. The material for these four walls may therefore be fabricated in the factory, be shipped in a knocked-down condition, and be bent and assembled at some remote point. However, when the structure is set up and assembled, it is extremely strong and rigid.

The top and bottom of the structure may be further reinforced by the top and bottom walls. In the arrangement shown, the top and bottom walls consist of simple heavy boards or panels 15. It will be seen that the side and rear walls project somewhat above the top of the front wall and the wings or flanges on the latter. Also, the upper portion of the inner half of the rear reinforcing rib 12 is cut away so that the effective top of the inner half of this rib lies in the same horizontal plane as the top of the front wall as indicated at 16. The top and bottom walls are cut away on the inner side along the entire rear edge and along the side edges to within a short distance of the front as indicated at 17, so as to produce a portion of reduced dimensions that will fit within the side and rear walls when the top and bottom walls are set in place; the top and bottom walls resting against the edges of the front wall and its wings and against the shoulders 16 on the 110

2
inner half of the rear reinforcing rib. That portion of each of the top and bottom walls that lies in front of the front edges of the side sheets 5 and 6 is left unmutilated so as to conceal the front edges of the upward and downward projections of these sheets. The top and bottom may conveniently be secured in place by means of ordinary wood screws 18 passing through the same into the front 10 wall or panel, and other screws passing through the side and rear walls into the edges of the top and bottom.

The top and bottom are preferably set back from the front face of the device so 15 that when the device is built into the wall A of a house or other building, the front edges of the top and bottom will be concealed by said wall. Consequently only the front face 20 of front wall of the device is exposed to view when the latter is built in and is, therefore, the only outer surface of the device that needs be attractively finished.

While I have illustrated and described with particularity only a single preferred 25 form of my invention, I do not desire to be limited to the exact structural details thus illustrated and described; but intend to cover all forms and arrangements which come within the definitions of my invention constituting the appended claims.

I claim:

1. A shell comprising a thick front wall having rearwardly-directed wings at the sides, side and rear walls of sheet metal, 35 said wings having deep narrow longitudinal grooves in their rear edges, the forward marginal portions of the side walls fitting into said grooves and being adapted to be moved into and out of the grooves through the open sides of the latter, and fastening means passing through each wing and that portion of the side wall embraced thereby.

2. A shell comprising a front wall, side walls of sheet metal extended laterally at 45 their rear ends to form two rear wall sections, a bracing strip lying between said rear wall sections and having deep grooves into which the said sections extend, and fastening means passing through said strip and through that portion of each of said sections embraced thereby.

3. A shell comprising a front wall, thick narrow pieces connected to said front wall and forming the front portions of the side walls, said pieces having deep grooves extending lengthwise thereof in their rear

edges, sheet metal side wall members fitted at their front ends into said grooves, said grooves being of such a shape as to permit the sheet metal members to be moved into and out of the same through their long open sides, and small bolts passing through each of said grooved pieces and through the sheet metal embraced thereby.

4. A shell comprising a front wall having thick rearwardly-directed wings at the sides, each wing having a deep groove extending lengthwise in its rear edge, two sheet metal elements each bent to form a side wall and a rear wall section, the front ends of each of 60 said sheet metal elements being fitted into one of the aforesaid grooves, and a bracing strip lying between said rear wall sections and having in opposed sides deep grooves 65 into which the said sections fit.

5. A shell comprising a front wall having thick rearwardly-directed wings at the sides, each wing having a deep groove extending lengthwise in its rear edge, two sheet metal elements each bent to form a side wall and a rear wall section, the front ends of each of 70 said sheet metal elements being fitted into one of the aforesaid grooves, a bracing strip lying between said rear wall sections and having in opposed sides deep grooves 75 into which the said sections fit, and bolts passing through said wings and said bracing strip and through the sheet metal portions embraced thereby.

6. A shell comprising a front wall having thick rearwardly-directed wings at the sides, each wing having a deep groove extending lengthwise in its rear edge, two sheet metal elements each bent to form a side wall and a rear wall section, the front ends of each of 80 said sheet metal elements being fitted into one of the aforesaid grooves, a bracing strip lying between said rear wall sections and having in opposed sides deep grooves 85 into which the said sections fit, and bolts passing through said wings and said bracing strip and through the sheet metal portions embraced thereby.

In testimony whereof, I sign this specification.

GEORGE R. MEYERCORD.
